(57) **CLAIM**

The ornamental design for a facsimile machine, as shown and described.

DESCRIPTION

FIG. 1 is a perspective view of a facsimile machine;
FIG. 2 is a front view thereof;
FIG. 3 is a top view thereof;
FIG. 4 is a right-side view thereof;
FIG. 5 is a left-side view thereof;
FIG. 6 is a rear view thereof;
FIG. 7 is a bottom view thereof; and,
FIG. 8 is another perspective view with a paper tray in an extended position and a paper stopper in a rotated position.
The broken line showing is for illustrative purposes only and forms no part of the claimed design.
The drawing FIGS. 2-7 are drawn in an enlarged scale.
